UNITED STATES PATENT OFFICE.

MARION W. PITNER, OF CHICAGO, ILLINOIS.

GENERATOR.

No. 911,440.

Specification of Letters Patent.

Patented Feb. 2, 1909.

Application filed March 26, 1906. Serial No. 308,099.

To all whom it may concern:

Be it known that I, MARION W. PITNER, a citizen of the United States, residing at Chicago, in the county of Cook and State of Illinois, have invented new and useful Improvements in Generators, of which the following is a specification.

This invention relates to generators of the type employed in connection with hydrocarbon heaters or burners for vaporizing gasoline or other liquid hydrocarbon fuel.

It is a well known fact that gasoline and analogous hydrocarbon oils contain acids which are highly injurious to metals, and that in consequence not only are the generators as now generally used injuriously affected by the fuel coming in direct contact with the metal, but there is produced within the generator under the action of the acids a sediment which is extremely liable to clog the outlet or injector orifice of the vaporizer. Furthermore, it has been found that the liquid fuel coming into direct contact with the metal surface of the generator, which in practice becomes highly heated, results in an uneven pulsatious vaporization of the fuel and consequently in an irregular, fluxatious feeding of the vapor to the heater or burner. Attempts have been made to cure this latter objection by filling the generating chamber with sand, charcoal or the like, or by employing therein wire cable or asbestos cord, these methods being objectionable, however, to the extent that they failed to prevent the hydrocarbon coming into direct contact with the metal with the above noted deleterious results and at the same time offered an objectionable resistance to the movement of the gasoline or vapor, thus retarding its proper flow and causing an irregular, uneven feeding thereof to the burners and at the same time necessitating the employment of an increased amount of pressure for forcing the fuel through the generator.

The present invention, which comprehends lining the chamber with a non-combustible material of a nature to resist the deleterious action of the acids in question, has for its objects to provide a comparatively simple, inexpensive lining which may be readily applied for use, one whereby direct contact of the fuel with the inner metal walls of the chamber is obviated, thus preventing the formation of a sediment within the generator, and one whereby a gradually uniform

heating of the interior of the vaporizer is insured, thus insuring uniform conversion of the fuel into, and an even flow of vapor to the burner.

With these and other objects in view, the invention comprises the novel features of construction and combination of parts more fully hereinafter described and particularly pointed out in the claim.

In the accompanying drawings, there is illustrated a central, longitudinal sectional view of a generator embodying the invention.

Referring to the drawing, 1 designates my generator which as illustrated herein serves to be employed in connection with vapor lamps and it comprises a suitable length of metal tubing, which is exteriorly threaded at opposite ends and is adapted to extend above the lamp in a position so as to be acted on by the heat from the lamp.

The tube is provided with a lining 5, composed of asbestos or other suitable material and extends on the inner surface nearly the entire length of the same so as to provide a chamber 6 at one end of the tube and into this chamber is inserted a thimble 4' having a surrounding flange in which is arranged a screen 4, the flange serving to contact with the terminal of the chamber 6. A nut 2, having a cone shaped opening 6' therein which registers with an injector opening 3, whereby communication is had with the screen and thimble, and the nut engages the screw threads on one end of the tube by means of which the flanged portion of the thimble is clamped between the nut and the terminal of the screw threaded end of the tube, whereby to hold the thimble in proper position within the chamber 6.

In practice, the lining which is not subject to the deleterious action of the acids contained in the hydrocarbon, will effectually protect the interior of the generator and prevent direct contact of the oil with the metal, thus obviating formation of the sediment as before explained, and will at the same time insure a gradual heating of the interior of the vaporizer, thus causing proper, gradual vaporization of the oil and insuring a consequent steady flow of the vapor through the injector orifice 3. It will be observed that by employing this form of lining within the generator the necessity for employing sand and other material within the generator is obviated and that in conse-

quence the device is adapted for accommodating a greater supply of hydrocarbon which may be fed slowly through the tube, thereby deriving the full action of the heat and insuring its proper and complete conversion into vapor.

Having thus fully described my invention, what I claim is:

- A hydrocarbon oil vaporizer comprising
10 a metal tubing with oppositely disposed externally screw threaded ends, a lining within the tubing, and extending nearly the length of the same, a chamber formed between the end of the lining and the end of
15 the tube, a thimble inserted within said chamber, said thimble having a flange pro-

vided with a screen secured thereto, a nut having a cone shaped opening therein, said nut also having an injector opening communicating with said cone-shaped opening, 20 said nut serving to engage the screw threaded end of the tube, so as to clamp the flange of the thimble against the terminal of the tube and against the nut, substantially as specified.

In testimony whereof, I affix my signature in presence of two witnesses.

MARION W. PITNER.
